[57] CLAIM

The ornamental design for a combined refrigerator and microwave oven, as shown and described.

DESCRIPTION

FIG. 1 is an enlarged perspective view of a combined refrigerator and microwave oven, showing my new design, the door of the storage compartment is shown in a closed position;

FIG. 2 is a front elevational view thereof;

FIG. 3 is a right side elevational view thereof, the opposite side being a mirror image;

FIG. 4 is a rear elevational view thereof;

FIG. 5 is a top plan view thereof;

FIG. 6 is an enlarged perspective view thereof, the door of the storage compartment is shown in an opened position;

FIG. 7 is a front elevational view of another embodiment of a combined refrigerator and microwave oven; and,

FIG. 8 is a right side view thereof, the opposite side being a mirror image.

The bottom view of the design is plain.
